UNITED STATES PATENT OFFICE.

ELBERT PEETS, OF CLEVELAND, OHIO.

PROCESS OF CLOSING CAVITIES IN TREES.

Application filed July 15, 1925. Serial No. 43,715.

The invention relates to an improvement in the art of closing and protecting open cavities in trees by a new process employing a curtain of metal or other strips set in a 5 groove cut out into the wood around the mouth of the cavity, the object of the curtain being to form a tight and strong but elastic wall, closing the cavity, and, without need of interior filling, supporting the healing 10 callus.

One form of the invention is illustrated in the accompanying drawings in which Figure 1 is a cross section through a decayed tree showing on one side the original decayed wood and on the other the cavity excavated and cut ready for setting the curtain; Fig. 2, a cross section showing location of curtain and bracing; Fig. 3, a front view of an excavated tree, showing installation of curtain; Fig. 4, a vertical section of same; Fig. 5, a vertical section through a narrow cavity, showing curtain strips overlapped; and Fig. 6, a section showing subsequent growth of the healing 25 callus.

The best material for making the strips or slats or plates which comprise the closure curtain is metal, especially steel, zinc, or aluminum, but hard wood, or a composition with characteristics similar to wood, may be used.

The decayed wood 1 is cut away and the surface 2 of the sound wood is painted with a disinfecting preservative. The mouth of the cavity is trimmed smooth and is cut with a bevel 3. Just inside this bevel a groove 4 is cut. A strip 5 of metal or other strong material is cut to proper length and one end is set in the groove 4 at one side of the cavity, at an angle with that side, and the free end of the strip is rotated and lowered into the groove in the other side of the cavity. The grooves should be of such depth and the strip of such length that the strip 40 cannot be removed from its position except by reversing the movement by which it was inserted. A number of strips are set in place the lower edge of each resting upon the upper edge of the strip previously set. 45 When the widest point of the cavity is reached it is better to start at the top and

work down, setting each strip below the previous one. Since the last two or three strips cannot be inserted by employing a 55 rotating movement they can be inserted by bowing or bending and springing them into place.

When the cavity begins at the ground the curtain may be begun below the surface of the soil, or an ordinary concrete filling 6 60 may be brought up to a convenient point at which to begin the curtain.

When the cavity is wide the strips comprising the closure have to be thick in order to have sufficient strength. In that case they 65 are set edge to edge, the lower edge of one strip resting on the upper edge of the one below it as shown in Fig. 4. When the cavity is narrow, the strips need not be so strong and can be of thinner material. In 70 that case the groove in the wood is cut twice as wide as the thickness of the material and the thin strips 11 are overlapped, the lower edge 12 of one strip being brought down over the upper edge 13 of the one below it, as 75 shown in Fig. 5.

In the treatment of large cavities in moist-wooded trees provision is made for the ventilation of the cavity. This is done by leaving a small opening 8 in the curtain. A 80 piece of wire gauze 9 is cemented over the opening and a pad of absorbent cotton 10, back of it, prevents the entrance of spores and insects.

In every case the entire outer surface of 85 the closure is painted with a heavy protective paint or asphalt cement.

Tie-bolts 7 are used, tying together the opposite walls of the cavity, to prevent the mouth of the cavity from spreading. 90

I claim:

1. For cavities in trees, a closing curtain consisting of a plurality of plates supported by a means permitting the movement, relatively to the tree, of the edge portions of 95 said plates adjacent to said tree.

2. In the treatment of cavities in trees, a closing wall consisting of metal slats, the ends of said slats being set in a continuous groove cut in the wood. 100

In testimony whereof I affix my signature.
ELBERT PEETS.
